UNITED STATES PATENT OFFICE.

GILLES HOLST AND EKKO OOSTERHUIS, OF EINDHOVEN, NETHERLANDS, ASSIGNEES
TO NAAMLOOZE VENNOOTSCHAP PHILIPS GLOEILAMPENFABRIEKEN, OF EINDHOVEN, NETHERLANDS.

ELECTRIC DISCHARGE TUBE.

Application filed July 28, 1923, Serial No. 654,481, and in France February 21, 1923.

The present invention relates to electric discharge-tubes, more particularly it relates to discharge-tubes being provided with an incandescent cathode.

5 It is known to compose the incandescent cathode of such devices of a highly refractory metal, such as for example tungsten.

According to the present invention incandescent cathodes of discharge-tubes are at 10 least at their surface made of hafnium, i. e. the element the atomic number of which is 72. Hafnium is highly refractory and has a low constant of Richardson. The said metal has consequently the advantage that at a temperature 15 at which the speed of volatilization is exceedingly small it has a very high emission of electrons.

According to the invention, it is also possible to make only the surface of glowcathodes 20 of discharge-tubes of hafnium. In this case the surface of a glowing body of other materials such as tungsten may be covered with hafnium.

Discharge-tubes with glowcathodes according 25 to the invention are quite suitable for use as X-ray tubes, rectifiers, receiving- and generating tubes or amplifiers for wireless telegraphy and telephony and other purposes.

30 The accompanying drawing shows a discharge-tube with three electrodes, viz an incandescent cathode, an anode and a grid, such as are generally applied as receivers or amplifiers for wireless telegraphy, telephony or other purposes.

In the drawing a closed envelope 1 which may consist of glass or the like is provided with a stem 9 supporting the electrodes.

The electrodes are concentrically arranged 40 within each other. The anode 2, consisting for example of nickel, is shaped as a nearly closed cylinder and is supported by its current-lead 5. The grid 3 consists of a coiled

wire of suitable metal, for example nickel or molybdenum and is supported by the current- 45 lead 6. The incandescent cathode 4 is a wire stretched between current-leads 7 and 8.

The current-leads 5, 6, 7 and 8 are hermetically sealed into the stem 9.

The envelope 1 may be highly evacuated in 50 any known manner.

According to the invention the incandescent cathode 4 may consist of hafnium. It may also consist of a core of a suitable refractory material, having a covering of hafnium; 55 the core may consist for example of tungsten.

What we claim is:—

1. An electrode for an electric discharge tube comprising a cathode containing hafnium. 60

2. An electric discharge tube comprising a cathode the surface of which contains hafnium.

3. In electron discharge tubes, a cathode adapted to emit electrons, said cathode comprising a core of conducting refractory material and a coating of hafnium. 65

4. An electron emitting cathode comprising a filamentary conductor containing hafnium. 70

5. An electron emitting cathode comprising a filamentary conductor the surface of which contains hafnium.

6. An electron emitting cathode comprising a filamentary conductor having a coating 75 of hafnium.

7. An electron emitting cathode comprising a core of tungsten coated with a film of hafnium.

8. A cathode for electron-discharge devices 80 having the element hafnium as a constituent thereof.

In testimony whereof we affix our signatures.

GILLES HOLST.
EKKO OOSTERHUIS.
